APPARATUS FOR JOINING METALLIC STRIP

William C. Lang, Willoughby, Ohio

Application February 7, 1947, Serial No. 727,038

8 Claims. (Cl. 219—4)

1

This invention relates to the method of and apparatus for joining metallic strip that is fed from a plurality of pay-off reels to a processing unit, such as cleaning or coating or both, in a manner to maintain continuous operation of the process which, in the coating process, obviously requires that there be no interruption.

In conventional practice in the treatment of steel strip produced in coils of great length by cold rolling methods, it is necessary to have slack producers of the elevator type of thirty to fifty feet in height with several loops of strip on the elevator carriage or to have looping pits of even greater depth so that the trailing end of the exhausted coil may be stopped in its travel momentarily for shearing and joining it to the leading end of the new coil without stopping the strip in the line. If, for example, when the strip is moving from one thousand to three thousand feet per minute and the welding operation for joining the strip ends requires twenty seconds, it is necessary to store one thousand feet of slack to allow the line to operate at the set line speed. Such lengths of slack are impractical to handle and cause difficulties, such as tangling of the strip.

Other disadvantages of conventional practice of paying out strip from a coil to a processing unit are that the coils from the mill are out of balance or become off balance when transferred to the processing unit or when mounted and clamped on the pay-off reel of the processing unit. Also the coils are sometimes not wound with their edges in true alignment or are mounted on the pay-off reel in a manner that the edges of the new coil are not in true alignment with the predetermined line-up of the processing unit. Such unbalance and misalignment cause irregularities of operation of the line resulting in jerking of the strip in the line from an out of balance coil, etc.

It is among the objects of the present invention to provide a method of automatically shearing the trailing end of one coil of strip and joining it to the sheared leading end of another coil while the strip is moving at line speed without the use of slack producers or looping pits.

Another object of the invention is the provision of means for balancing the coil on the pay-off reel and for lining up the coil on the pay-off reel to permit proper tracking of the strip through the processing unit.

Another object of the invention is the provision of apparatus for shearing and welding a moving strip.

Still another object of the invention is the provision of a novel form of pay-off reel arranged in pairs so that the reel paying off strip to the line is always in the same position when paying off strip except during the welding operation and the empty reel is in the same position each time for

2

loading a new reel. The invention will become more apparent from a consideration of the accompanying drawings, constituting a part hereof, in which like reference characters designate like parts, and in which

Fig. 1 is a side elevational view diagrammatically illustrating apparatus for joining metallic strip embodying the principles of this invention;

Fig. 2 a similar view illustrating a modified form of welding electrodes;

Fig. 3 a front elevational view of the cut-off mechanism employed in the structures of Figs. 1 and 2;

Fig. 4 a view in cross section taken transversely of the cutting rolls of Fig. 3;

Fig. 5 a cross sectional view transversely of the axis of a plurality of welding rolls;

Fig. 6 a front elevational view of the welding roll shown in Fig. 5;

Fig. 7 a top plan view of a terminal plate for a plurality of welding electrodes;

Fig. 8 a cross sectional view illustrating the welding electrodes and retracting apparatus therefor;

Fig. 9 a side elevational view of the electrode terminal structure shown in Fig. 7;

Fig. 10 an end elevational view, and Fig. 11 a side elevation, partially in cross section, of a switch for energizing the cutting mechanism;

Fig. 12 a side elevational view of a plurality of pay-off reels mounted for angular movement; and

Fig. 13 a top plan view of a motor drive and control circuits for a plurality of pay-off reels.

With reference to Fig. 1 of the drawing, the numeral 1 designates a powered pay-off reel for feeding metallic strip 2 which, as shown in Fig. 1, has been unreeled to the last strand and has just released a spring loaded contact lever 3, the details of which will be hereinafter explained. The

numeral 1a designates a second pay-off reel having a similar spring loaded contact lever 3a, which by pressure of the strip coiled thereon is in the depressed position. The reel 1a is paying off or feeding metallic strip 2a that passes over a guide roll 4 and between a pair of pulling squeegee rolls 5 and 6 by which it is fed against a deflector plate 7 which preferably has side guides, not shown. Strip 2, payed off from reel 1, passes between shearing rolls 8 and 9 having shear blades 10 and 11 and then passes between a pair of back tension squeegee rolls 12 and 13 to welding rolls 14 and 15. In accordance with this invention, one of the two reels 1 and 1a is always

feeding strip to a processing unit such as a cleaning or plating bath (not shown) at a predetermined line speed which by means of the apparatus herein described is not interrupted when the strip has been exhausted from the reel because

the trailing edge is automatically joined to the

leading edge of the other reel without interrupting the process.

The shearing roll 8 and its accompanying back-up roll 9 are not tightly pressed together as the squeegee rolls 5 and 6, a slight clearance being allowed at the tangent point of the rolls to avoid distortion of the strip by the notch 11 of the back-up roll 9 when the shear is not operating. Shear rolls 8 and 9 are motor driven at line speed and are interconnected by gearing to maintain operative alignment of the shearing knife 10 and notch 11.

As will be hereinafter explained, the spring loaded contact lever 3 of the pay-off reel 1 energizes the actuator that extends the shear blade 10 at a predetermined point of the shearing revolution. Contact lever 3 also initiates rotation of the pulling squeegee rolls 5 and 6 and the driving motor of pay-off reel 1a in a manner hereinafter explained, and at a predetermined time interval after the release of contact lever 3, when the last strand of the coil unwraps, the welding tips of roll 14 are projected in contact with the strip to spot weld the trailing end of strip 2 with the leading end of strip 2a. The welding squeegees 14 and 15 are likewise not pressed tightly together and are driven synchronously at strip speed by separate motors, not shown. A surface cleaning device 16 contacts the lower welding roll 15.

With reference to Figs. 3 and 4, the shearing roll 8 and its back-up roll 9 are shown in detail. The shearing blade 10 is extensible through a slot 10a of the roll by means of a bar 17 disposed in a slot 18 of the hollow roll shaft 19, the bar 17 being displaced vertically by an operating bar 20 that is actuated by solenoids 21 and 22. The blade actuating bar 17 and the operating bar 20 are tapered throughout their length so that axial movement of the operating bar 20 will extend or retract the shear blade 10. Coil springs 23 are provided to take up the shock when the blade contacts the sheet strip.

The welding roll and back-up roll 14 and 15, respectively, are shown in the enlarged and sectional views of Figs. 5 and 6 of the drawings. The roll 14 is provided with radial holes 24 in which are disposed electrodes 25 connected by coil springs 26 to plungers 27 that are actuated by a tapered bar 28, the bar being operated by solenoids 29 and 30. The electrodes 25 are energized with electrical current by terminal rings 31 and 32 connected to a suitable source of electrical current and necessary controls. The electrical terminals are axially and angularly staggered as shown in Fig. 6 to provide a multiple of terminal contacts for engaging the sheet strip to be welded when passing between the welding roll and the back-up roll. The welding roll is insulated so that no current can escape to the sheet strip except through the terminal ends at the time of welding and the back-up roll 15 is provided with a highly conducting surface material 33, such as copper, which is kept clean by a means 16 biased by a coil spring 16a to maintain yielding contact with the back-up roll.

The pay-off reel 1 is shown enlarged in Figs. 10 and 11 in which the contact arm 3 is shown as biased by a spring 34. The arm 3 carries an electrical contact 35 which energizes an electrical control circuit when it engages terminal 36, the circuit consisting of the slip-ring 37, the ring 38 and the bushes 37a and 38a, respectively. When the arm 3 is down, as when the coil is wrapped therearound, the control circuit is open and when

the last wrap of the coil releases contact arm 3 contactor 35 closes the circuit with terminal 36 and energizes the control circuit.

As shown in Figs. 12 and 13, the pay-off reels 1 and 1a are mounted on a yoke 39 which is mounted on a shaft 40 journaled in a standard 41 and the yoke 39 is rotatable by means of a gear wheel 42 driven by a pinion 43 of a motor 44, Fig. 13. As shown in Fig. 13, the pay-off reels 1 and 1a have their shafts 45 and 46 separately driven by motors 47 and 48. These motors operate as either driving or back tension motors and the shafts 45 and 46 are journaled in the yoke 39 by bearings 49 and 50. Shaft 40 is journaled in bearings 51 and 52 having block rings 53 and 54 and has a square end for engagement with the yoke 39. Shafts 45 and 46 of reels 1 and 1a carry stationary rings 55 and 56, respectively, that are actuated by forks 57 and 58 connected by levers 59 and 60 to motors 61 and 62. These motors are energized by contact levers in the path of the strips 2 and 2a so that when the latter are out of alignment motors 61 and 62 are energized to move the forks and thereby the shafts 45 and 46 to adjust the reels to proper alignment.

The shafts 45 and 46 also carry collector rings 63 and 64 with their associated brushes 65 and 66 which supply current to the motors 47 and 48 and 61 and 62 and to contact points of the contact levers 3 and 3a. Reels 1 and 1a carry balancing blocks 69 which provide a method of dynamically balancing reels 1 and 1a by spinning the reels with the motors 47 and 48 before the coil is welded and the balancing weights 69 may be locked in their adjusted position. Reels 1 and 1a are provided with clamping drums 70 and 70a.

In the modified form of the pay-off, shearing and welding mechanism shown in Figs. 2, 7, 8 and 9, the strip 2 is pulled by the squeegee rolls 5 and 6 and strip 2a by squeegee rolls 12 and 13. The strip is sheared by a shearing block 71 which is connected to be operable by the welding block 72. A shear knife 73 is mounted on the welding and shearing block 74 and contacts shear block 71 to shear off the trailing end of strip 2. Blocks 72 and 74 are mounted to travel with the strip at strip speed until the shearing and welding operation have been completed. The blocks then open and return to their starting position. The blocks 72 and 74 are biased to their normally open position and when released, close on the strips 2 and 2a, the end of strip 2a being initially magnetically held by the block 72 energized by magnetic coils 79. The welding electrodes 12a, Figs. 7 and 8, of the shearing and welding blocks are actuated in the direction of contacting the strips 2 and 2a by solenoids 75, 76, 77 and 78. Current is supplied to the welding electrodes 12a through the shaft 80, Fig. 8, insulated from block 72 by bushing 81.

The operation of the strip joining apparatus will first be described in connection with Figs. 1, 3, 4, 5, 6, 10, 11, 12 and 13 of the drawings which relate to the apparatus shown in Fig. 1. As viewed in Fig. 1, the sheet strip 2 has been payed off reel 1 to the point where the last strand has unwrapped and relieved the pressure on contact 3, which, as shown in Figs. 10 and 11, is biased by spring 34 to the extended position in which position contact 35, Fig. 11, engages terminal 36 of the control circuit which energizes solenoids 21 and 22, Fig. 3, of the shear roll 8 to extend the shear blade 10 at a predetermined point of the shearing revolution or stroke. The shear roll 8 and the back-up roll 9 are driven at the same

speed as the strip 2. The actuating contact 3 simultaneously also starts rotation of the pulling squeegees 5 and 6, and the driving motor 48, Fig. 13, of the pay-off reel 1a, so that the end of the new strip 2a is fed against the deflector plate 1 which feeds the strip into perfect alignment with the strip 2. At a predetermined time after contact 3 is released, the welding terminals 25, Fig. 5 of the welding roll 14 are extended outward to contact the strip 2a and spot weld it with strip 2, thus joining the lapped-over trailing and leading ends of strips 2 and 2a. After the shearing blade 10 has made its shearing stroke, it is retracted before it again comes into shearing position.

When the welding operation is completed, the 15 pulling rolls 5 and 6 discontinue feeding the strip 2a and act as a back drag to keep the line tension constant until slack between reel 1a and guide roll 4 is taken up. Then the back drag is supplied by the driving motor 48 of pay-off reel 1a. Driving motor 47, in the meantime, had been 20 supplying back tension to strip 2 until this strip was exhausted from pay-off reel 1, at which time actuating lever 3 starts back tension squeegee rolls 12 and 13 to supply back tension. When all 25 the slack of the strip 2a between reel 1a and guide roll 4 has been taken up and back drag is being supplied by the driving motor 48 of pay-off reel 1a, the driving motor acting as a generator or dynamic brake, rotation of the shearing roll 8 is halted and the roll is displaced along the line of its shaft until it clears the edge of the strip and is out of register therewith. Guide roll 4 and squeegee rolls 5 and 6 are then lowered in a vertical direction until there is no downward component of tension on the surfaces of rolls 4 and 6, the strip being in a straight line from the top of the coil of reel 1a to a tangent point of the rolls 12 and 13. The tension on squeegee rolls 5 and 6 is then released and, together with the 30 guide roll 4, these rolls are retracted along their axis out of line of travel of strip 2a. The pay-off reels 1 and 1a are then rotated through the gear drive 42 and 43, Figs. 12 and 13, in a clockwise direction until reel 1a takes the position of reel 1 and vice versa. Rolls 4, 5 and 6 are then 35 raised above the strip line and are replaced to the position shown in Fig. 1 in line with the strip but above it. A new coil is then mounted on the reel 1 that has now taken the position of reel 1a, Fig. 1, and the device is ready for the next shearing and welding after the operator has sheared the end of the new coil and feed it over guide roll 4 and between the squeegee rolls 5 and 6 against deflector plate 8.

In operation of the modified form of pay-off apparatus shown in Fig. 2, the operation of the contact arm 3 and the pay-off reels 1 and 1a, the rolls 12, 13 and the squeegees 5 and 6 is the same as described in connection with Fig. 1 of the drawings. The welding apparatus, however, differs as has been described, and in this case the leading end of the new coil 2a is held magnetically to the welding block 72 by coils 79, Fig. 6. When lever 3 of reel 1 is actuated, the back drag tension on the strip 2 is transferred from the driving motor 47 of reel 1 to the squeegee rolls 12 and 13 and, at the same time, the two welding and shearing blocks 72 and 74 are released to move in the direction of travel of the strip, as indicated in dotted lines in Fig. 2 of the drawings.

When blocks 72 and 74 start to move, the solenoid 76 of the block 72 is energized, as is the solenoid 77 of block 74, forcing the two blocks into clamping position on the leading and trailing

ends of the strips 2 and 2a. On the upward motion of the block 74, shear knife 73 contacts shear block 71, shearing off the trailing end of strip 2. The blocks then move with the strip and the welding tips 72a (Fig. 8) of the blocks are actuated to weld the two strips together. After the welding operation the blocks 72 and 74 separate and their strip holding magnets de-energize, the shearing block 71 starting below the strip pass line with the block 74. When the strip 2 leaves the back tension squeegees 12 and 13, the back tension is applied to squeegees 5 and 6 until the slack between reel 1a and squeegees 5 and 6 is taken up. The back tension is then supplied by the driving motor 48 of reel 1a, Fig. 13. As soon as blocks 72 and 74 begin forward movement with the strip, the driving motor of reel 1a is started in a direction to pay off strip from reel 1a to overcome the static inertia of reel 1a. As the welding operation is completed blocks 72 and 74 return to their starting position, as shown in the solid lines in Fig. 2. Tension on squeegees 12 and 13 is then released and roll 12 and shearing block 71 are retracted in a direction parallel to the face of the strip until they are out of the line of travel of the strip. Squeegees 5 and 6 are then lowered in a vertical plane until there is no downward component of tension on roll 6. The tension on squeegees 5 and 6 is then released and roll 6 is retracted out of line of travel of the strip. Reels 1 and 1a then rotate in a clockwise direction, the reel 1 assuming the position of the reel 1a and vice versa. Rolls 6 and 12 in the shearing block 71 are then raised and again assume their original position, as shown in Fig. 2.

It is evident from the foregoing description of the invention that the method of shearing and joining the leading and trailing edges of a plurality of coiled strips automatically without interrupting line travel of the strip eliminates the need for elevators or looping pits, and is carried on without interruption of the processing of the strip, such as cleaning or plating or both, as the case may be.

Although the invention has been described in a general way, it is evident that various modifications are possible in the use of electrical and mechanical actuating devices within the knowledge of those skilled in the art without departing from the principles herein set forth. For example, hydraulic actuating mechanism, pneumatic or mechanical movement may be substituted for the electrical controls and actuators, and instead of spot welding, seam welding or other means of joining the strip may be employed.

I claim:

1. Apparatus for paying off metallic strip to a processing unit comprising a plurality of pay-off reels on which coils of strip are alternately loaded and payed off to the processing line, means for shearing the trailing edge of the strip of one reel and joining it to the sheared leading edge of the other reel, means for aligning the trailing and leading ends of said strips in overlapped and juxtaposed position, and means for joining said overlapped strip, said means being energized by an actuator in response to the unwinding of the last strand of the coiled strip on said reels and said respective means being operative on said strips at a predetermined line speed of the strip through the processing unit and joining unit.
2. Apparatus for paying off metallic strip to

a processing unit comprising a plurality of pay-off reels mounted on a common support, means for rotating said support to alternately place said reels in paying-off and loading position, each of said reels having a drive motor and each reel having a switch arm in engagement with the last strand of the coiled strip on said reels which arms are normally depressed but released when the last strand of strip is unwound, means energized by said reel switch for shearing the trailing edge of one reel and for feeding the leading edge of the other reel to overlap said trailing edge, and means also energized by said reel switch for welding said overlapped strip edges while passing to the processing line.

3. Apparatus for paying-off metallic strip to a processing unit comprising a plurality of pay-off reels mounted on a common support, means for rotating said support to alternately place said reels in paying off and loading position, each of said reels having a drive motor and each reel having a switch arm in engagement with the last strand of the coiled strip on said reels which arms are normally depressed but released when the last strand of strip is unwound, drive rolls for feeding said strip after it leaves said reels, shearing mechanism for shearing the trailing edge of the strip, and welding means for joining the trailing and leading edges of the strip, the operation of said drive rolls, shearing and welding devices being initiated by the switch arm of the pay-off reel when released by the last strand of the strip coil.

4. Apparatus for paying off metallic strip to processing units comprising a plurality of pay-off reels on which the strip is initially coiled, said reels being mounted on the ends of a yoke which is journaled for rotation whereby the pay-off reels are bodily movable angularly about the yoke axis to bring the strip in parallel alignment in the direction of its travel to the processing unit, said reels being journaled in said yoke and having individual motors for rotating the reels or to act as a magnetic brake when the strip is pulled, guide rolls for said strip and squeegee rolls for driving the strip whereby the trailing edge of one strip and the leading edge of another strip may be drawn to a plurality of welding rolls, a guide for bringing the strips in superposed relation, a shearing roll for cutting the trailing edge of one strip preliminary to their being brought in contact by the said guide means, said welding rolls and shearing rolls having separate actuating means and control means including a switch arm carried by the pay-off reels normally displaced to open position by the last strand of the strip coil on the reel and which when released energizes the several actuating means for the drive, shear and welding rolls to effect shearing, overlapping and welding of the trailing and leading edges of the strip without interrupting the travel of the strip to the processing unit.

5. Apparatus for paying off metallic strip to a processing unit comprising a plurality of pay-off reels on which coils of strip are alternately loaded and payed off to the processing line, means for shearing the trailing edge of the strip of one reel and joining it to the sheared leading edge of the other reel, means for aligning the trailing and leading ends of said strips in overlapped and juxtaposed position, and means including a welding roll having radially spaced electrodes for joining said overlapped strip, said means being

energized by an actuator in response to the unwinding of the last strand of the coiled strip on said reels and being operative on said strips at a predetermined line speed of the strip through the processing unit and joining unit.

6. Apparatus for paying off metallic strip to a processing unit comprising a plurality of pay-off reels on which coils of strip are alternately loaded and payed off to the processing line, means for shearing the trailing edge of the strip of one reel and joining it to the sheared leading edge of the other reel, means for aligning the trailing and leading ends of said strips in overlapped and juxtaposed position, means including a welding roll having radially spaced electrodes for joining said overlapped strip, and means including a rotary shear roll for shearing the trailing end of the associated coil, said means being energized by an actuator in response to the unwinding of the last strand of the coiled strip on said reels and being operative on said strips at a predetermined line speed of the strip through the processing unit and joining unit.

7. Apparatus for paying off metallic strip to a processing unit comprising a plurality of pay-off reels mounted on a common support, means for rotating said support to alternately place said reels in paying-off and loading position, each of said reels having a drive motor and each reel having a switch arm in engagement with the last strand of the coiled strip on said reels which arms are normally depressed but released when the last strand of strip is unwound, shearing mechanism including a rotary shear roll for shearing the trailing edge of the strip, and welding means including a welding roll having radially spaced electrodes for joining the trailing and leading edges of the strip, the operation of said drive rolls, shearing and welding devices being initiated by the switch arm of the pay-off reel when released by the last strand of the strip coil.

8. Apparatus for paying off metallic strip to a processing unit comprising a plurality of pay-off reels mounted on a common support, means for rotating said support to alternately place said reels in paying off and loading position, each of said reels having a drive motor and each reel having a switch arm in engagement with the last strand of the coiled strip on said reels which arms are normally depressed but released when the last strand of strip is unwound, means energized by said reel switch for shearing the trailing edge of one reel and for feeding the leading edge of the other reel to overlap said trailing edge, and means also energized by said reel switch for welding said overlapped strip edges while passing to the processing line at a predetermined line speed.
